UNITED STATES PATENT OFFICE.

FREDERICK W. VODOZ, OF CHICAGO, ILLINOIS.

FUNNEL AND STRAINER.

Application filed July 13, 1921. Serial No. 484,315.

To all whom it may concern:

Be it known that I, FREDERICK W. Vodoz, a citizen of the United States, residing at Chicago, in the county of Cook and State 5 of Illinois, have invented certain new and useful Improvements in Funnels and Strainers, of which the following is a specification.

The invention relates to folding funnels and strainers.

10 One of the objects of the invention is to provide an improved folding funnel that may be collapsed into relatively small dimensions.

Another object of the invention is to 15 provide a similar structure provided with a strainer by means of which mechanically suspended particles or other objectionable ingredients in the liquid passing thru the funnel may be caught and held.

20 Another object is to provide a collapsible or foldable funnel that may be contracted and inserted within the container, to which it is substantially inseparably attached, when not in use and which will automatically expand for use when removed from the receptacle.

Another object is to provide an improved funnel and strainer especially well adapted for radiators of automobiles, which may be 30 collapsed and inserted in the radiator when not in use and which is inseparably connected to the screw cap closure, permitting the closure to be screwed to the neck of the radiator with the funnel therein.

35 Another object is the provision of means connected with the collapsible funnel to prevent unauthorized removal of the closure cap and the "motor meter" usually connected therewith.

40 Other, further and more specific objects of the invention will become readily apparent, to persons skilled in the art, from a consideration of the following description when taken in conjunction with the drawings, wherein:—

Fig. 1 is a broken away plan view showing parts in section, taken on line 1—1 of Fig. 2.

Fig. 2 is a substantial vertical central 50 section of the device when expanded for use.

Fig. 3 is an enlarged detail.

In all the views the same reference characters are employed to indicate similar parts.

55 The device is shown in connection with an automobile radiator 5 having a neck 6

threaded as at 7, for a screw cap closure 8. A "motor meter" 9, provided with a stem 10 which passes thru screw cap 8, is held therein by a nut 11, as usual in devices of 60 this character.

The funnel structure, as illustrated, consists of four spring pressed arms 12 and 13 forming one pair made of a single piece of wire, and 14 and 15 forming another pair 65 made of a single piece of wire. Each of the arms is bent into a terminal eye 16 at its outstanding end for connection to a flexible cloth or fabric 17 of which the major portion of the funnel is composed. The 70 wires forming the arms 12, 13, 14 and 15 are each bent into a spring eye 18 providing vertical members 19 and 20, which are connected together at the bottom by an eye 21. The separation of the members 19 75 and 20 is not so great as to prevent them from being introduced into the neck of the radiator 5. The flexible fabric, or sheet 17, may be attached to the arms by loops 22, or the like, at convenient intervals. The members 12 and 13 contain spring loops 24 similar to those indicated by the reference character 18 and at the bottom they are bent into an eye 25 similar to the eye 21. Thru the eyes 21 and 25 a screw 26 is passed 80 and pivotally secured by the screw is a cross bar 27 which is longer than the greatest diameter of the throat in the neck 6 of the radiator, so that when the cross bar 27 is moved to the position as shown in dotted 85 lines at 27', the device may be inserted in the radiator, but it cannot again be conveniently removed therefrom.

Now, from the foregoing description, it is manifest that the outstanding arms 12, 95 13, 14 and 15 may all be moved inwardly until the arms are substantially parallel with the parts 19 and 20, whereupon the fabric or sheet 17 will be folded and the whole device can be pushed into the radiator 100 thru the throat 6. The fabric 17 may be substantially water-proofed and provided with a hole at its central lower portion thru which the liquid will pass. A refinement of this structure is the introduction of the strainer 30, overlying the hole and used to filter or strain out any objectionable matter that may be contained in the liquid or water that is to be passed into the radiator. The filter or strainer 30 may be, and preferably 105 is, not larger in diameter than the orifice in the throat 6 of the radiator, so that it may

be pushed downwardly and into the radiator without being deformed or folded as in the case of fabric 17.

A further refinement of the device is the introduction of a rod 32 having a lower flat end 33 and extending upwardly and axially of the throat 6 to a bend 34, where it is flat, as at 35, and is provided with an eye in the end 36 to receive the stem 10 of the motor meter 9. The rod 32 serves as means for inseparably holding the screw cap 8 in association with the device and, furthermore, when the nut 11 surrounding the stem 10 of the motor meter is soldered in place, it serves as a means for preventing the unauthorized removal of the motor meter, or in other words, it locks the motor meter to the radiator. When it is desired to close the radiator by the cap member 8 of the throat 6, it is only necessary to push down on the top of the motor meter, whereupon the rod 32 will transmit the stress to the bottom of the wire structure, causing the outstanding arms 12 to 15, inclusive, to be collapsed, and the fabric connecting the arms to be folded, so that the entire device will thereupon be moved into position for convenient insertion in the throat 6.

The body part 17 of the funnel may be made of a flexible medium that is not quickly deteriorated by dampness and heat, ordinary cotton duck or canvas when properly treated with a preservative will serve the purpose.

After the device has been collapsed and pushed into the radiator throat the cap may be rotated on the stem 10 to screw it to the neck 7 without rotating the funnel structure.

While I have herein shown a single embodiment of my invention for the purpose of clear disclosure, it will be manifest to persons skilled in the art, that considerable change in the general arrangement and configuration of the parts is permissible within the scope of the appended claims.

Having described my invention what I claim as new and desire to secure by Letters Patent, is:—

1. In combination with a liquid receptacle having a relatively small opening, of a collapsible funnel for insertion in the opening when collapsed; means for inseparably se-

curing the funnel to the receptacle and a closure for the opening inseparably secured to the funnel.

55

2. In combination with a liquid receptacle having a relatively small opening and a closure therefor of a collapsible funnel for insertion in the opening when collapsed and means for inseparably securing the funnel and closure to the receptacle.

60

3. In combination with a liquid receptacle having a relatively small opening and a closure therefor, of a collapsible funnel for insertion in the receptacle thru the opening when collapsed; means for inseparably securing the funnel and closure to the receptacle and spring pressed arms for automatically opening the funnel when a part is removed from the receptacle.

65

4. In combination with a liquid receptacle having a relatively small opening; a threaded cap for closing the opening; a collapsible funnel for insertion in the receptacle when collapsed and located between the cap and receptacle when extended; an axially located vertical rod connected to the funnel and to the cap to permit rotation of the latter and spring pressed means to extend the funnel when removed from the receptacle.

70

5. In combination with an automobile radiator of a threaded cap to close the filling opening therein; a spring pressed extensible and collapsible funnel inseparably connected to the radiator by means permitting rotation of the cap and means for inserting the funnel into the radiator sufficiently to permit attachment of the cap thereto.

75

6. In combination with an automobile radiator having a filling opening and a screw threaded cap therefor and a temperature indicating device extending outwardly from the cap; a spring pressed, collapsible and contractible funnel for insertion in the radiator when contracted and means connecting the funnel to the cap and to the indicating means to permit its relative rotation of the cap and associated parts and prevent unauthorized removal of the parts from the radiator.

80

In testimony whereof I hereunto subscribed my name.

FREDERICK W. VODOZ.
